Primary Examiner—A. Hugo Word*Assistant Examiner*—Marcus Jackson*Attorney, Agent, or Firm*—David L. Baker, Rhodes & Ascolillo[57] **CLAIM**

The ornamental design for an indicator pole for towed vehicles, as shown and described.

DESCRIPTION

FIG. 1 is a reduced perspective view of an indicator pole for towed vehicles showing my new design, with the broken line showing for illustrative purposes only and forming no part of the claimed design;

FIG. 2 is an enlarged explored front elevational view thereof, with the opposite sides being a mirror image, and with the pole broken away in the center for clarity of illustration only;

FIG. 3 is a top plan view; and,

FIG. 4 is a bottom plan view.
